(57) **CLAIM**

The ornamental design for a holder for CAD/CAM blanks, as shown and described.

DESCRIPTION

FIG. 1 is a perspective view of a holder for CAD/CAM blanks showing our new design;

FIG. 2 is a bottom view thereof;

FIG. 3 is a rear elevation view thereof;

FIG. 4 is a front elevation view thereof;

FIG. 5 is a side elevation view thereof;

FIG. 6 is a top plan view thereof; and,

FIG. 7 is a perspective view thereof.

The broken line showing is for illustration purposes only and forms no part of the claimed design.
